UNITED STATES PATENT OFFICE

WILLIAM BROAD, OF BEAVER FALLS, PENNSYLVANIA, ASSIGNOR TO HARRY E. MCCLAIN,
OF PITTSBURGH, PENNSYLVANIA

VIBRATOR

Application filed April 17, 1928. Serial No. 270,670.

My invention relates to vibrators, and more particularly to vibrators for massaging the limbs and torso of a patient.

In massaging the limbs and torso of a patient, relatively heavy blows are required from the vibrator as compared with the blows delivered by a vibrator adapted for application to the more tender portions of a patient's body, such as the face. In the latter type of vibrator, rapid and relatively light blows are delivered for improving the circulation in the flesh near the outer surface thereof.

In massaging the limbs and torso of a patient, it is frequently desired to massage muscles lying at some distance from the surface. Occasion frequently arises for massaging groups of muscles that collectively form a tough cord. Effective treatment of such portions of the body requires that a relatively heavy blow be delivered to the patient opposite the area being treated.

Vibrators of the general class to which this invention relates are usually designed to operate on a standard alternating-current electric light circuit. The most common frequency of such alternating currents is sixty (60) cycles. Fire regulations require that household appliances which are adapted for interchangeable use on ordinary light circuits shall take but a few amperes.

Accordingly, the power available at a frequency of sixty (60) cycles is insufficient to deliver the required heavy blows when the vibrator is applied to the body of a patient. To reduce the number of strokes delivered by the vibrator, and thereby enable the vibrator to deliver a more effective blow at each stroke, I provide a rectifier in circuit with the vibrator that reduces the number of strokes delivered by the vibrator to approximately one-half the frequency of the alternating electrical current supplied to the vibrator.

The accompanying drawings illustrate the present preferred embodiment of the invention, in which:

Figure 1 is an elevational view partially in section of a vibrator embodying my invention,

Figure 2 is a similar view taken at substan-

tially right angles to the view shown in Figure 1,

Figure 3 is a sectional view taken along the section line III—III of Figure 1, and

Figure 4 is a sectional view taken along the section line IV—IV of Figure 2 and illustrating the electrical connections for the vibrator.

In carrying out the present invention, there may be provided a casing 2 of any appropriate shape and material, although I prefer to form it as a hollow cylinder of suitable insulating material. Attached to a casing 2 by any desired means, such for instance as screws 4, is a handle 5 preferably disposed on the end 6 of the casing and at substantially the center of the casing. The handle 5 is formed by a grip 7, preferably of electrical insulating characteristics such as hard rubber or molded phenolic condensation products.

A bolt or rod 8 extends longitudinally through the grip 7 for securing the ends of a metallic strap 9 of U shape in depressions formed at the ends thereof. The strap 9 is provided with openings 10 through which the screws 4 extend. An electromagnet 11 is carried by a base 12 of non-magnetic material such as copper or a copper alloy, secured by screws 14 to the inner surface of the end 6. The electromagnet 11 comprises a pair of windings 15 mounted on a core 16. The core 16 is supported by screws 17 that extend into the base 12. The armature 18 for the electromagnet is supported by screws 19 that extend through a metallic strap 20 overlying layers of soft iron 21 constituting the body of the armature through a block 22 of non-magnetic material such as copper or a copper alloy, and are imbedded in a vibrating element in the form of a lid or cover 24 for the vibrator.

The cover 24 is provided on its inner surface with a plate 25, the ends of which are provided with bosses 26. The plate 25 is secured to the cover 24 by screws 27. Pintles 28 extend through openings in lugs 29 projecting inwardly from the base 12 along a center line of the casing 2. The pintles are threaded into the bosses 26 and are

provided with lock nuts externally of the lugs 29.

With the foregoing construction, the lid or cover 24 is adapted to turn about the pintles 28 upon the attraction of the armature 18 to the core 16. The amount of turning movement of the lid 24 is controlled by a resilient block 31, seated in a ferrule 32 having a threaded extension 34 for making a threaded engagement with the material of the cover 24 and the cooperating resilient block 35, seated in a ferrule 36 carried by a screw 37 extending through a threaded sleeve 38 in the end 6.

15 The screw 37 is provided with a knurled head 39 disposed externally of the casing 2. The ferrule 36 is carried by a leaf spring 40 that tends to hold the resilient block 35 in engagement with the block 31. By adjusting the position of the head 39 and the screw 37, the relative position of the blocks 31 and 35 is varied, thereby controlling the clockwise turning movement, as viewed in Figure 3, of the cover 24 about the pintles 28. If 25 desired, a small space may be left between the blocks 31 and 35.

Return movement of the cover 24, upon the release of the armature 18 by the electromagnet, is secured by separate blocks 41 and 42 disposed on the opposite side of the casing from the blocks 31 and 35. Block 41 is adjustably supported by a screw 43 having a knurled head 44 of a construction and operation similar to that of the screw 37 and head 39. The block 41 is kept in engagement with the block 42 and under such pressure as to tend to move the lid 24 in a clockwise direction about the pintles, as viewed in Figure 3. The cover 24 is provided with 40 threaded openings 45 for the reception of stems 46 for applicators 47.

The applicators 47 are preferably disposed on opposite sides of the handle 5 for applying uniform pressure to each applicator from the handle. The exact shape of the applicators may be varied as desired by removing the stems 46 from the openings 45 and inserting the stems of other type of applicators. The flat surface of the vibrating elements may be used on the body of a patient with applicator if desired. With the foregoing construction, the cover 24 is alternately turned in a counter-clockwise direction, as viewed in Figure 3, by the attraction 55 between the core 16 and the armature 18 and in a clockwise direction by the expansion of the blocks 41 and 42, the latter being compressed when the cover 24 is turned in a counter-clockwise direction by the action of 60 the electromagnet.

Accordingly, each applicator 47 turns about the pintles 28 to deliver a blow to a patient upon each operating cycle of the armature 18 to and from the core 16. By 65 reason of the size of the applicator and by

reason of the nature of the service for which the vibrator is intended, namely, that of applying powerful blows to the limbs and torso of a patient, I find that better operation is obtained by operating the vibrator upon an alternating current having a frequency less than the common sixty (60) cycle frequency. Accordingly, I provide a current rectifier 48 in circuit with the electromagnet. A copper oxide rectifier is suitable for reducing the frequency of the current although it is to be understood that other types of rectifiers may be used.

The rectifier 48 permits the current to traverse itself in but one direction, thereby 80 reducing the number of pulsations of the vibrator to one-half the frequency of the alternating current applied to the rectifier. A snap switch 49 is carried by the end 6 in proximity to the handle 7 in order that 85 an operator can start or stop the vibrator by the motion of a finger without removing the hand from the grip 7.

Referring to Figure 4, the circuit for the vibrator extends from a terminal 50 of a plug through a conductor 51, the rectifier 48, a conductor 52, one of the windings 15, a cross-over conductor 54 to the other winding 15, through the other winding 15, a conductor 55, the switch 49 and a conductor 56, to the other terminal 57 of the plug.

While I have illustrated and described the present preferred embodiment of my invention it is to be understood that various changes may be made in the invention without departing from the scope of the appended claims.

I claim:

1. In a vibrator, a casing, a handle secured to one surface of the casing, a vibrating element constituting a surface of the casing opposite the handle, applicators carried by the vibrating element and disposed on opposite sides of said handle, whereby pressure applied to the handle is uniformly distributed to the applicators.

2. In a vibrator, a casing, a single handle secured to one surface thereof, a vibrating element associated with the surface of the casing substantially opposite to the handle, and applicators carried by the vibrating element, said applicators being disposed on opposite sides of the plane of the handle, whereby pressure applied to the casing by the handle is distributed to the applicators.

3. A vibrator comprising a casing, a cover, a pivotal support for the cover attached intermediate the cover, means for imparting an oscillatory movement to the cover about the pivotal support, and applicators carried by the cover on opposite sides of the axis of the pivotal support for delivering a double blow during each cycle of movement of the cover.

4. A vibrator comprising a casing, a cover

for an end of the casing and having a disc shape with a flat outer surface, means for supporting said disc substantially along a diameter thereof, and means mounted within 5 the casing and imparting oscillatory movement to the cover, whereby the cover oscillates about said support to impart a wave-like movement to flesh being treated.

5. A vibrator comprising a casing, a disc-shaped closure member for one end of said casing and having a substantially flat outer surface, a supporting means for said closure member effective along substantially a diameter of said closure member, means mounted 10 within the casing for oscillating said closure member, and a handle mounted on the opposite end of the casing and substantially in alignment with the axis about which the first-named closure oscillates, whereby upon 15 the application of the oscillating closure member to a patient, pressure applied to the vibrator at the handle is distributed evenly on opposite sides of the axis of oscillation of said oscillating closure, and a wave-like motion of considerable pressure and surface 20 extent is imparted to the patient.

25 In testimony whereof I have hereunto set my hand.

WILLIAM BROAD.
